GRIPPER FOR HOSIERY STRIPPERS

William J. Merrigan, Jr., Charles S. Tiers, and Harry F. Wanamaker, Philadelphia, Pa., assignors to Proctor & Schwartz, Incorporated, Philadelphia, Pa., a corporation of Pennsylvania

Application February 29, 1932, Serial No. 595,878

12 Claims. (Cl. 223—26.3)

This invention relates to machines for removing stockings from forms, such as that disclosed in United States Letters Patent No. 1,126,619, and more particularly to the improved grippers 5 for such machines, as shown in the copending application of Harry F. Wanamaker, Serial No. 593,073, filed February 15, 1932.

When a stocking is held by the grippers as the form is withdrawn from the stocking, as described in the above noted patent, the more or less rapid relative movement between the form and the stocking fabric creates static electricity which causes the stocking to cling to the contact faces of the grippers. These contact faces heretofore have been composed of rubber, in view of the high frictional qualities of the rubber and the consequent efficiency in holding the stocking as the form is withdrawn therefrom.

Such clinging of the stocking, even though it 20 may be but momentary, prevents the stockings from being laid smoothly on the receiving table which operates below the grippers to receive the stockings as they are released by the grippers. There is a relative horizontal movement between the grippers and the receiving table and unless the stocking is completely released and falls at the proper time onto the table the stocking becomes wrinkled or folded on the table, requiring manual smoothening of the stocking, which is 25 undesirable.

The object of the present invention is to eliminate the clinging of the stockings to the contact faces of the grippers, so that each stocking will be fully released at the proper time to fall 35 properly onto the receiving table in a flat smooth condition thereon.

The construction and operation of the improved apparatus forming the subject of the present invention will be fully disclosed hereinafter, reference being had to the accompanying drawings, of which:

Fig. 1 is a side elevation of a cooperating pair of gripping jaws, in closed position, equipped in accordance with the principles of the present invention;

Fig. 2 is a view similar to Fig. 1 with the jaws in open position to release a stocking;

Fig. 3 is a longitudinal sectional elevation taken on the line 3—3, Fig. 1;

Fig. 4 is a transverse sectional elevation taken on the line 4—4, Fig. 3;

Fig. 5 is a fragmentary side elevation of a modified form of the invention; and

Fig. 6 is a perspective view of the gripper pad 55 shown in Fig. 5.

As shown in Figs. 1, 2, 3 and 4, the gripper comprises a pair of cooperating jaws 1 and 2 respectively, which are pivotally mounted on a supporting bar 3 and arranged to be opened and closed by a relatively oscillating shaft 4 through a lever 5 and links 6, 6.

The upper jaw 1 is provided with a head 10 having a longitudinal opening or slot 11 in which is suitably mounted a pad-carrying block 12.

The lower jaw 2 is provided with a similar head 20 having a longitudinal slot 21 in which is suitably mounted a pad-carrying block 22.

In the block 12 of the upper jaw is secured a contact pad 15 and in the block 22 of the lower jaw is secured a contact pad 25, between the contact faces 15a and 25a of which a stocking x is adapted to be gripped, so that as the form is drawn out of the stocking the stocking will be held substantially stationary by the grippers.

Such relative movement between the form and the stocking creates static electricity that causes the stocking to cling to the contact surfaces of the gripper pads as above noted, which, as also noted above, heretofore have been made of rubber.

In the course of a series of experiments directed to elimination of the clinging of the stocking to the contact pads, it has been found that by making the contact pad on one jaw, preferably the lower jaw, of wood or an equivalent of wood, and by making the contact pad in the other jaw of rubber with suitable plugs composed of a different material imbedded therein, such for example as plugs composed of rolled woven fabric or other bunched non-metallic threads or fibers, the effect of the static electricity created by the relative movement between the form and the stocking is nullified.

As shown in detail in Figs. 3 and 4, the contact pad 25 of the lower jaw 2 is composed of wood, preferably a relatively hard wood such as maple, while the contact pad 15 of the upper jaw 1 is composed of rubber of a more or less resilient compressible nature and provided with relatively spaced plugs 30 composed of rolled woven fabric, with the lower ends of the plugs imbedded in the rubber and the upper ends preferably projecting slightly above the contact surface 15a of the pad 15.

If desired, the rubber pad 15 can be supplanted by a wooden pad, or its equivalent, but it has been found more effective to retain one pad of rubber, due to the frictional characteristics which

- more firmly holds the stocking as the form is withdrawn therefrom.
- As the stocking, when gripped by the jaws, is more or less warm, as a result of having passed through a drier just prior to the stripping of the stocking from the form by the grippers, the contact face of the rubber pad, after a long period of continuous use, tends to soften and to become contracted by the pressure exerted thereon through the medium of the opposed and cooperating wooden pad 25 in the lower jaw of the grippers. Such contracting of the rubber pad, which ordinarily would necessitate frequent adjustment of the jaw-controlling mechanism to provide uniform gripping of the stockings by the cooperating jaws, is eliminated by the firmer plugs 30 composed of the rolled woven fabric or of longitudinally parallel bunched threads or other non-metal fibers which are imbedded in the rubber pad, the portion 31 of the pad against which the plugs 30 bear, and which is confined in the retaining cavity 13 of the carrier block 12, affording the necessary resilient seat for the plugs, contracting of the pad in the direction of the length of the plugs which would result in expansion of the pad in a direction transverse of the plugs being eliminated by reason of the lower portion 31 of the pad being confined in cavity 13 of the carrier block 12.
- The pads 15 and 25 are provided with counter-bored openings 16 and 26 respectively which receive the retaining bolts 17 and 27 respectively that hold the pads in the carrier blocks 11 and 21 respectively.
- In some instances the pads may be reversed, that is, the wooden pad may be placed in the upper jaw and the rubber pad may be placed in the lower jaw. Under these conditions the stocking hanging over the rear upper edge of the rubber pad drags on said edge as the stocking moves out of the grippers upon release thereby, and in order to eliminate such dragging of the stocking the pad is provided with a rearwardly extending flange or shelf 35, as illustrated in Figs. 5 and 6. The flange being flexible readily bends under the weight of the stocking to form a smooth curved surface at the rear of the pad to prevent any dragging of the stocking over the otherwise relatively sharp unyielding edge of the pad.
- If desired, the rubber pad may be faced with leather or fabric, as shown at 36 in Figs. 5 and 6, in place of having the plugs 30 imbedded in the rubber, the leather or fabric facing having a fairly satisfactory degree of frictional quality which will hold the stocking under the pressure exerted by the grippers, but which will be immune to the effects of the static electricity and which at the same time will prevent the softening and contracting of the rubber under long periods of continuous use.
- We claim:
1. In a machine for removing stockings from forms, the combination of a pair of cooperating jaws arranged to grip a stocking on a form therebetween for stripping the stocking from the form upon relative movement being effected between the form and the stocking held by the jaws, and means devoid of electrostatic attraction for the stocking carried by the jaws for gripping contact with the stocking to prevent cohesion between the stocking and the jaws as a result of the relative movement between the stocking and the form.
  2. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of a material devoid of electrostatic attraction for the stocking to prevent cohesion between the stocking and the pad as a result of the relative movement between the stocking and the form.
  3. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of wood devoid of electrostatic attraction for the stocking to prevent cohesion between the stocking and the pad as a result of the relative movement between the stocking and the form.
  4. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of a material having relatively high frictional qualities and provided with inserts composed of a material devoid of electrostatic attraction for the stocking to prevent cohesion between the stocking and the pad as a result of the relative movement between the stocking and the form.
  5. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of rubber and provided with inserts composed of a material devoid of electrostatic attraction for the stocking to prevent cohesion between the stocking and the pad as a result of the relative movement between the stocking and the form.
  6. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of rubber and provided at the stocking-engaging face thereof with inserts composed respectively of groups of fibers arranged substantially parallel with the corresponding ends of the fibers of each group disposed in a plane approximately coincident with the plane of the said contact face of the pad.
  7. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, at least one of said pads being composed of rubber and provided at the stocking-engaging face thereof with inserts composed respectively of groups of fibers arranged substantially parallel with the corresponding ends of the fibers of each group disposed in a plane approximately coincident with the plane of the said contact face of the pad.

- the form and the stocking held by the jaws, a contact pad carried by each jaw for engagement with opposite sides of the stocking respectively, at least one of said pads being composed of rubber and provided with plugs composed of rolled woven fabric imbedded in the rubber and projecting above the face of the pad arranged to engage the stocking. 80
8. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, one of said pads being composed of rubber and provided with plugs composed of rolled woven fabric imbedded in the rubber and projecting above the face of the pad arranged to engage the stocking and the other of said pads being composed of wood. 85
9. In a machine for removing stockings from forms, the combination of a pair of cooperating jaws arranged to grip a stocking on a form therebetween for stripping the stocking from the form upon relative movement being effected between the form and the stocking held by the jaws, a contact pad carried by each jaw for engagement with opposite sides of the stocking respectively, and a flexible shelf adjacent and projecting outwardly from one edge of the pad of the lower jaw for supporting the stocking beyond the pad. 90
10. In a machine for removing stockings from forms, the combination of a pair of cooperating jaws arranged to grip a stocking on a form therebetween for stripping the stocking from the form upon relative movement being effected between the form and the stocking held by the jaws, a resilient pad on the lower jaw for contact with the under-side of the stocking, and a flexible shelf adjacent and projecting outwardly from one edge of the pad of the lower jaw for supporting the stocking beyond the pad. 100
11. In a machine for removing stockings from forms, the combination of a pair of cooperating jaws arranged to grip a stocking on a form therebetween for stripping the stocking from the form upon relative movement being effected between the form and the stocking held by the jaw, a resilient pad on the lower jaw for contact with the under-side of the stocking, a flexible shelf adjacent and projecting outwardly from one edge of the pad of the lower jaw for supporting the stocking beyond the pad, and a covering on said pad and said shelf composed of material devoid of electrostatic attraction for the stocking to prevent cohesion between the stocking, the pad and the shelf as a result of the relative movement between the stocking and the form. 105
12. In a machine for removing stockings from forms, the combination of a pair of cooperating jaws arranged to grip a stocking on a form therebetween for stripping the stocking from the form upon relative movement being effected between the form and the stocking held by the jaws, a resilient pad on the lower jaw for contact with the under-side of the stocking, a flexible shelf adjacent and projecting outwardly from one edge of the pad of the lower jaw for supporting the stocking beyond the pad, a covering on said pad and said shelf composed of material devoid of electrostatic attraction for the stocking, a wooden pad carried by the upper jaw and cooperating with the said resilient pad of the lower jaw to grip a stocking therebetween and to prevent cohesion between the jaws and the stocking as a result of said relative movement between the stocking and the form. 110
